BASE SCRAPING APPARATUS

Zoltan W. Miklos, University Heights, Ohio, assignor to General Electric Company, a corporation of New York

Application February 29, 1952, Serial No. 274,126

3 Claims. (Cl. 90—24)

My invention relates to apparatus for basing electric lamps, discharge devices and the like, and more particularly to apparatus for removing the excess solder used in connecting leads to the metal shells of bases.

An object of my invention is to provide apparatus for scraping off the excess solder projecting beyond the periphery of the metal shell of the base of an electrical device so that said device can be readily inserted and removed from a socket. The apparatus is especially concerned with the removal of solder from the metal shell of a base which must be either pushed or screwed into a relatively closely fitting barrel or sleeve and wherein any excess solder projecting from said base may prevent it from entering into the socket or being easily removed therefrom should the base be forced into the socket. One type of incandescent lamp made defective by a very small amount of projecting solder is a very small lamp used in conjunction with airplane instruments; which lamp is inserted bulb-foremost into a socket and which has no appreciable protruding portion enabling it to be securely grasped and pulled from the socket.

Another object of my invention is to provide base scraping apparatus suited to automatic operation in high speed basing apparatus, and to a clamping device for retaining the lamp in position in the holding means therefor during the scraping operation. To this end, means are provided for advancing a knife, preferably conforming to the shape of the shell of the base, to a position in close proximity or directly into contact with the base shell, as desired; when a lamp is presented at a work station occupied by said scraping apparatus and for moving the knife along the base to effect the scraping thereof. The base clamping device in association with the scraping mechanism is comprised of non-reversible means movable against the end of the base to locate it longitudinally in the basing apparatus and prevent it from being forced therefrom by the scraping mechanism during its interval of operation.

Still other objects and advantages of my invention will appear from the following detailed description of a species thereof and from the accompanying drawing.

In the drawing, Fig. 1 is a perspective view of base scraping and clamping apparatus comprising my invention at the time of its arrangement at operative relation to a lamp retained by basing apparatus and with a portion broken therefrom to show enclosed actuating means; and Fig. 2 is a perspective view on a larger scale of said lamp and the end of the scraping knife of said apparatus at the time the said knife is advancing to engagement therewith.

The scraping and clamping apparatus shown in the drawing is located at one work station along the path of movement of the lamp carrier of automatic basing apparatus and completes a cycle of operation each time a lamp 1 is positioned at said work station by one of a succession of indexing motions of said carrier. The lamp 1 is held in an inverted (base up) position on a vertical axis by a head 2 at the periphery of the turret 3 com-

2

prising the carrier and is located below a portion of the clamping apparatus 4 overhanging the course of movement thereof and opposite the scraping apparatus 5 located radially outward from said turret 3 and said path.

5 Relatively no lateral displacement of the lamp 1 can occur when the cycle of operation of the apparatus is initiated as the bulb 6 thereof is almost completely contained in a pocket in the holder 7 of the head 2 and as the base 8 thereof is almost completely surrounded by the fixed jaws 9 and 10 of said head 2. Vertical movement of the lamp 1, on the other hand, is possible at this moment since neither the base 8 or the bulb 6 are gripped and the latter is so small as to allow it to pass upward between the jaws 9 and 10 should an upward movement of the lamp 1 be initiated.

The first operation of the apparatus provides for the clamping of the base 8 of the lamp 1 in the head 2 by the apparatus 4 and effects this clamping operation by lowering the end of the stud 11 into engagement with 20 the contact 12 at the center of the insulation button 13 at the end of the base 8. The stud 11 is, in effect, a part of and has the same movement as arm 14 into which it is screwed and which is located within an open longitudinal channel in the body 15 of the clamping apparatus; and said stud 11 is carried down against the base 8 by a rocking or pivotal movement of said arm 14 about the pivot pin 16 bridging said channel. The pressure of engagement of the stud 11 against the base 8 is sufficient to force said base 8 down into the head 2 to the extent that the flange 17 at the upper end of the metal base shell 18 seats firmly against the top surface of the jaws 9 and 10 of the head 2 and has the effect of correcting any tilting of said base 8 which might interfere with the proper scraping of the shell 18.

35 The stud 11 and the arm 14 are normally retained at a raised position above the base 8 by the contraction force of a helical spring 19 located within adjoining cavities in said arm 14 and the body 15 of the apparatus and connected between pins in said arm 14 and said body 15. The downward movement of the stud 11 and the arm 14 results when the slide 20, in contiguous slide-ways of the body 15 behind the cover plate 21, is moved toward said arm 14 and by so doing advances the wedge shaped end 22 thereof as far as possible into the space above the shoe 23 pivoted on a pin 24 extending across the bifurcated end of said arm 14. The force with which the wedge end 22 of the slide 20 is introduced and, accordingly, the pressure with which stud 11 presses against the base 8, is determined by the resilience of the two springs 25—25 connecting ears at the end of the slide 20 to the opposite ends of the cross pin 26 of the operating means of the apparatus. The strength of these springs 25—25 is such that the cross pin 26 is held tightly against the right end (Fig. 1) of the cross slot 27 for most of the motion of the operating arm 28 which extends down into a central opening in the slide 20; however, the springs 25 allow the cross pin 26, which is held by the operating arm 28, to advance in the cross slot 27 when the operating force is excessive. Corresponding and somewhat longer clearance slots (not shown) in the opposed side walls of the body 15 of the apparatus avoid any interference with the full movement of the cross pin 26.

40 The time interval of operation of the apparatus is determined by operating means (not shown) actuated by the basing machine in the manner of other apparatus in combination therewith and like said other apparatus is caused to occur at a corresponding interval after a lamp 1 has been advanced to the work station before the present apparatus. The operating means effects vertical actuation of the rod 30 connected to the arm 31 on the opposite end of the shaft 32 from the operating arm 28, and

causes said arm 28 to turn with said shaft 32 which is supported by the upstanding support lug 33 of the body 15 of the apparatus. This completes the operations of the clamping apparatus prior to the scraping of the base, and the operation is reversed after said scraping has occurred. Throughout the period of operation, the body 15 of the apparatus remains at a fixed position determined by its attachment to the overhanging arm 34, only partially shown, of the frame of the basing machine.

The next operation to occur is that of the scraping apparatus, which apparatus advances the end of a knife 35 to engagement with the directly opposing portion of the metal outer shell 18 of the base 8. The knife 35 is attached to a slide 36 within ways behind the retaining plates 37-37 in the body 38 of the scraping apparatus and is advanced toward the base 8 by a rocking or pivoting motion of a lever 39 pivoted at 40 to the body 38 and moving the slide 36 by means of pin 41. This advancing operation of the knife 35 is under the control of the main operating apparatus of the basing machine which presently effects an upward movement in the connecting rod 42, which motion is terminated when the end of the adjustable stop screw 43 on the lever 39 bears against the end of the body 38. A spring 44 connected between posts on the lever 39 and a portion of the body 38 serves to absorb the freedom of movement in the operation means so as to give more accurate control thereof.

The knife 35 engages an exposed portion of the base shell 18 in alignment with the space between the tips of the jaws 9 and 10 of the head 2 and at the elevation of the lower end of said base shell 18 inasmuch as the vertical column 45, which is the supporting means for the body 38, is then at a corresponding position. This position of the knife 35 places the sharp edge 46 thereof, formed by the upper and the curved end surfaces thereof, at a position below the solder 47 filling a triangular indenture in the base shell 18 and holding one of the leads 48 of the lamp 1, and permits said edge 46, which has a shape conforming to the curvature of the base shell 18, to scrape the excess protruding portion of the solder 47 from the base 8 by an upward movement thereof. The solder 47, in combination with the base shown, is the means of attaching the end of the lead 48, extending through a slit 49 in the base shell 18 at the edge of the indenture, to said base shell 18. Because of the small size of the parts, it is difficult to prevent the solder from protruding beyond said base shell 18.

The upward scraping movement of the knife 35 is initiated by a corresponding movement of the body 38 under the control of the operating apparatus (not shown) of the basing machine engaging and sliding the support column 45 upward in the frame portion 50, and lifts the entire scraping apparatus 5 sufficiently for the knife to pass over the entire vertical extent of the solder filling 47. The connecting rod 42 also follows the upward movement of the body 38 so that the knife 35 does not pull back from the base shell 18. The upward force applied to the base 8 is relatively great during the scraping movement of the knife 35; however, no movement can occur in said base 8 as the angularity of the matching faces of the shoe 23 and wedge 22 is such that the upward pressure of arm 14 and shoe 23 can not force the wedge 22 and slide 20 back from its position thereabove. The cycle of operation of the apparatus is completed upon retraction of the knife 35 from the base 8 and lowering of the body 38.

After the clamping and scraping apparatus 4 and 5 have separated from the lamp 1, the lamp can be pushed from the head 2 of the basing machine by an upward movement of the push rod 51 which extends through a vertical hole in the holder 7 below the bulb 6. Means are also provided in combination with the clamping apparatus for preventing the stud holding arm 14 and the wedge portion 22 of the slide 20 from advancing beyond a limit of operation in event of the absence of a lamp 1 from the head 2, said means being in the pin 52 extend-

ing across the bottom opening in the body 15 and blocking movement of the stud holding arm 14.

While I have described a preferred form of apparatus comprising my invention, I do not wish to be limited to the exact structure shown as it will be understood that many modifications of the precise manner in which my invention is carried into effect may be used without departing from the scope of the appended claims. In this connection it should be noted that the scraping apparatus could be used separately from the clamping apparatus as for instance, where the base is gripped by the basing machine, see Fagan Patent 1,724,831. It should also be noted that the scraping apparatus can be adjusted so that the knife 35 does not bear against the base shell 18 and can therefore be used to trim a solder mass located wholly outside the periphery of said base shell 18.

What I claim as new and desire to secure by Letters Patent of the United States is:

1. Apparatus for removing excess solder projecting from the flanged cylindrical shell of a base of an electric device comprising holding means encompassing the cylindrical shell with the exception of the solder and the adjacent shell portion for aligning the base with an axis, means for clamping the base in position in the holding means comprising an arm pivoted to one side of the axis and movable generally therewith into engagement with the end of the base and wedge means for moving the arm to seat the shell flange firmly against the holding means, said wedge means being non-reversible by pressure exerted by the base in the scraping operation, a knife located to one side of the axis, means for moving the knife toward the base holding means and into close proximity to said adjacent portion of the base shell at a position displaced axially on the opposite side of the solder from the clamping means and the shell flange, and means for moving the knife axially along the base shell toward said clamping means and said shell flange to scrape the excess solder therefrom.

2. Apparatus for removing excess solder projecting from the flanged cylindrical shell of a base of an electric device comprising holding means encompassing the cylindrical shell with the exception of the solder and the adjacent shell portion for aligning the base with an axis, means for clamping the base in position in the holding means comprising an arm pivoted to one side of the axis and movable generally therewith into engagement with the end of the base, and wedge means for moving the arm to cause the pressure of engagement thereof to seat the shell flange firmly against the holding means, said wedge means being non-reversible by pressure exerted by the base in the scraping thereof, a knife having a concave cutting edge conforming with the periphery of the base shell and located to one side of the said axis, means for advancing the knife toward the base holding means and into engagement with the base shell at a position displaced axially on the opposite side of the solder from the clamping means and the shell flange, and means for moving the knife axially along the base shell toward said clamping means and the shell flange to scrape the excess solder therefrom.

3. In combination with a carrier having thereon holders with pockets for accommodating electric lamps and indexing them to successive positions in a fixed path of travel, a clamping mechanism comprising a body portion mounted over said path of travel at one of said positions of the holders and having a downwardly opening horizontal channel in the bottom thereof, an arm mounted longitudinally in said channel for pivotal movement in a vertical plane about one of its ends and having a stud portion extending downwardly from an intermediate portion thereof to be located over a lamp in a holder, spring means connected to said arm to urge it upwardly about its pivot, a shoe member mounted on the end of said arm opposite its pivoted end for pivotal movement in a vertical plane, a slide member

mounted in said channel for longitudinal movement therein and in apposition to said arm, said slide member having a wedge-shaped forward end fitting between said shoe member and the upper wall of said channel, and actuating means connected through spring means to said slide to pull the slide forwardly to cause its wedge-shaped end to urge the said shoe downwardly and thereby pivot the arm downwardly to cause its said stud portion to engage the lamp and clamp it in said holder.
